ATTORNEY.

UNITED STATES PATENT OFFICE

111,886

DESIGN FOR A COMBINED LAMP AND SUPPORTING BRACKET

Samuel J. Zagel, Chicago, Ill.

Application July 2, 1938, Serial No. 78,236

Term of patent 7 years

To all whom it may concern:

Be it known that I, Samuel J. Zagel, a citizen of the United States of America, residing at Chicago, Cook County, Illinois, have invented a new, original, and ornamental Design for a Combined Lamp and Supporting Bracket, of which the following is a specification, reference being had to the accompanying sheet of drawings forming a part thereof.

I claim:

The ornamental design for a combined lamp and supporting bracket, as shown.

SAMUEL J. ZAGEL.
